UNITED STATES PATENT OFFICE.

HERMAN C. PRIEBE, OF BLUE ISLAND, ILLINOIS.

DRAFT GEAR.

Application filed December 12, 1922. Serial No. 606,522.

To all whom it may concern:

Be it known that I, HERMAN C. PRIEBE, citizen of the United States, residing at Blue Island, in the county of Cook and State 5 of Illinois, have invented a certain new and useful Improvement in Draft Gears, of which the following is a full, clear, concise, and exact description.

My invention relates to draft gears and 10 has for its objects the provision of an improvement in the construction of motion resisting mechanism and the means for carrying the same. A draft gear carrying out both objects of my invention includes a 15 coupler having a yoke formed with an outwardly facing spring receiving seat upon its inner end, said yoke having one of its sides of Y-shape with the stem of the Y at the outer portion of the yoke and the 20 branches of the Y at the inner portion of the yoke, a longitudinal spring having its inner end upon said seat, an outer follower enclosed by the yoke, and lever mechanism seated upon the branches 25 of the Y-shaped side of the yoke and engaged by the inner end of the aforesaid follower, the inner end of the yoke, and also by the outer end of the aforesaid spring.

The invention will be more fully explained 30 by reference to the accompanying drawings in which Fig. 1 is a plan view of the preferred form of gear shown in assembly with center or draft sills, parts being broken away and parts being shown in section; Fig. 2 is 35 a sectional view on line 2—2 of Fig. 1; Fig. 3 is a bottom plan view of a part of the structure; Fig. 4 is a sectional view somewhat similar to Fig. 2 but with more parts shown in elevation and some of the parts 40 being in changed positions; Fig. 5 is a sectional view on line 5—5 of Fig. 1; Fig. 6 is a perspective view of the preferred form of coupler yoke; Fig. 7 is a perspective view 45 of co-operating rockers that constitute the preferred form of lever mechanism, these rockers being illustrated in separated relation; and Fig. 8 is a perspective view illustrating the outer follower that is in assembly with the coupler yoke.

Like parts are indicated by similar characters of reference throughout the different 50 figures.

The center or other draft sills 1, 2 are assembled in any suitable way with the body 55 of the car as is understood by those skilled

in the art. The draft gear of my invention is interposed between these sills. This draft gear includes a coupler having a stem 3 and a yoke 4. The stem is formed with a transverse horizontal key slot therethrough 60 and at the inner end thereof while the outer end of the yoke is formed with similar slots 6 and 7 which are aligned with the slot in the stem. A key 8 is passed through all of these slots which, with the exception of the slot in the stem, are all longer than the width of the key so that the key may move longitudinally of the yoke in the operation 65 of the gear. This key also passes through slots 9 formed in the center sills, these slots also being longer than the width of the key to permit the key to move longitudinally 70 of the center sills.

The coupler yoke is generally of U-form 75 with one side thereof above the other. Cheek plates 10 and 11 are engaged by the inner end of the yoke to limit the extent to which the yoke may be moved inwardly. An outer follower 12 is surrounded or enclosed by the yoke and is engageable by the coupler butt 80 to be moved inwardly thereby. Cheek plates 13 and 14 are at the forward end of the gear and are engaged by the follower 12 to limit the extent of the outward movement 85 of the follower.

A key 15 is passed through slots formed 90 in the follower and center sills. This key is substantially immovable with respect to the outer follower longitudinally of the gear but may move with the follower as the slots 95 16 in the center sills that receive this key are longer than the width of the key. Another key 17 is passed through slots formed 100 in the inner end of the coupler yoke and the center sills, the slots 18 in the center 105 sills that receive the key being longer than the width of the key to permit travel of the key longitudinally of the center sills.

Motion resisting spring mechanisms 19, of 110 well known type, are interposed between the keys 15 and 17. The yoke of the coupler is formed with an outwardly faced spring receiving seat 20 upon the inner end of the yoke. The lower side of the yoke is of Y-shape with the stem 21 of the Y at the outer portion of the yoke and the branches 22 of the Y at the inner portion of the yoke. A coiled spring structure has its inner end upon said seat. A strap 24 partially surrounds the spring and is connected with the 115

inner portions of the Y-shaped side of the yoke, the strap, yoke and spring seat being preferably formed in one integral casting.

Rockers 25 are disposed within the space between the sides of the yoke and project into alignment with the springs at their lower ends, the upper ends of these rockers being in engagement one with the inner end of the follower 12 and the other with the inner end of the yoke. The rockers have opposed convex co-acting curved surfaces extending transversely of the gear, these rockers being maintained in assembly with the balance of the gear by having overhanging shoulders 26 which rest upon the branches of the lower yoke side. The spring 23, by engaging the lower portion of the inner rocker, co-operates with both rockers, the follower and the yoke in resisting draft strains. Parts of the rocker that are respectively engaged by the follower and the inner end of the yoke are desirably also convex in curvature whereby the places of engagement of the rockers with said follower and yoke change, this arrangement constituting the preferred form of lever mechanism co-operating with the spring mechanism and the balance of the gear in resisting motion.

30 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In a draft gear, the combination with 40 a coupler having a yoke carrying an outwardly facing spring receiving seat upon its inner end, said yoke having one of its sides of Y-shape with the stem of the Y at the outer portion of the yoke and the branches 45 of the Y at the inner portion of the yoke; of a longitudinal spring having its inner end upon said seat; a strap partially surrounding the spring and connected with the inner portions of the Y-shaped side of the yoke; an outer follower enclosed by the yoke; and two rockers having opposed convex co-acting curved surfaces extending transversely of the gear and seated upon the branches of the Y-shaped side of the yoke, 55 one of these rockers being engaged by the inner end of the aforesaid follower and the other of the aforesaid rockers being engaged by the inner end of the yoke, the latter rocker also having engagement with the outer end 60 of the aforesaid spring.

2. In a draft gear, the combination with 65 a coupler having a yoke carrying an outwardly facing spring receiving seat upon its inner end, said yoke having one of its sides of Y-shape with the stem of the Y at

the outer portion of the yoke and the branches of the Y at the inner portion of the yoke; of a longitudinal spring having its inner end upon said seat; a strap partially surrounding the spring and connected with the inner portions of the Y-shaped side of the yoke; an outer follower enclosed by the yoke; and two rockers having opposed convex co-acting curved surfaces extending transversely of the gear and seated upon the branches of the Y-shaped side of the yoke, 70 one of these rockers being engaged by the inner end of the aforesaid follower and the other of the aforesaid rockers being engaged by the inner end of the yoke, the latter rocker also having engagement with the outer end of the aforesaid spring, the parts of the rockers that are respectively engaged by the follower and the inner end of the yoke being of convex curvature.

3. In a draft gear, the combination with a coupler having a yoke formed with an outwardly facing spring receiving seat upon its inner end, said yoke having one of its sides of Y-shape with the stem of the Y at 80 the outer portion of the yoke and the branches of the Y at the inner portion of the yoke; of a longitudinal spring having its inner end upon said seat; a strap partially surrounding the spring and connected with the inner portions of the Y-shaped side of the yoke; an outer follower enclosed by the yoke; and lever mechanism seated upon the branches of the Y-shaped side of the yoke and engaged by the inner end of the aforesaid follower, the inner end of the yoke, and also by the outer end 85 of the aforesaid spring.

4. In a draft gear, the combination with a coupler having a yoke carrying an outwardly facing spring receiving seat upon its inner end, said yoke having one of its sides of Y-shape with the stem of the Y at the outer portion of the yoke and the branches of the Y at the inner portion of the yoke; of a longitudinal spring having its inner end upon said seat; an outer follower enclosed by the yoke; and two rockers having opposed convex co-acting curved surfaces extending transversely of the gear and seated upon the branches of the Y-shaped side of the yoke, 100 one of these rockers being engaged by the inner end of the aforesaid follower and the other of the aforesaid rockers being engaged by the inner end of the yoke, the latter rocker also having engagement with the outer end 105 of the aforesaid spring.

5. In a draft gear, the combination with a coupler having a yoke carrying an outwardly facing spring receiving seat upon its inner end, said yoke having one of its sides of Y-shape with the stem of the Y at the outer portion of the yoke and the branches of the Y at the inner portion of the yoke; of a longitudinal spring having 110

its inner end upon said seat; and outer follower enclosed by the yoke; and two rockers having opposed convex co-acting curved surfaces extending transversely of the gear 5 and seated upon the branches of the Y-shaped side of the yoke, one of these rockers being engaged by the inner end of the aforesaid follower and the other of the aforesaid rockers being engaged by the inner 10 end of the yoke, the latter rocker also having engagement with the outer end of the aforesaid spring, the parts of the rockers that are respectively engaged by the follower and the inner end of the yoke being of convex 15 curvature.

6. In a draft gear, the combination with a coupler having a yoke formed with an outwardly facing spring receiving seat upon its inner end, said yoke having one of its 20 sides of Y-shape with the stem of the Y at at the outer portion of the yoke and the branches of the Y at the inner portion of the yoke; of a longitudinal spring having its inner end upon said seat; an outer fol-

lower enclosed by the yoke; and lever mechanism seated upon the branches of the Y-shaped side of the yoke and engaged by the inner end of the aforesaid follower, the inner of the yoke, and also by the outer end of the aforesaid spring. 25

7. In a draft gear, the combination with a coupler having a yoke carrying an outwardly facing spring receiving seat upon its inner end; of a spring having its inner end upon said seat; an outer follower; and two rockers having opposed convex co-acting curved surfaces extending transversely of the gear, one of these rockers being engaged by the inner end of the aforesaid follower and the other of the aforesaid 40 rockers being engaged by the inner end of the yoke, the latter rocker also having engagement with the outer end of the aforesaid spring. 35

In witness whereof, I hereunto subscribe 45 my name this 6th day of December A. D., 1922.

HERMAN C. PRIEBE,
